UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ADAPTER FOR FIXTURE-SUPPORTING DEVICES.

Application filed March 26, 1921. Serial No. 455,916.

This invention relates to adapters for use with devices for supporting fixtures or other electrical appliances demountably. More particularly, the invention is concerned with 5 adapters for use in association with fixture supporting plugs of the general character described and illustrated in a copending application for Letters Patent of the United States filed by the present applicant on 10 March 5, 1920, Ser. No. 363,419. The supporting device shown in said copending application includes a hook adapted to engage a bridge carried with the bracket or appliance to be supported. In the fixture art, 15 however, it is not unusual for brackets to have threaded stems with which the supporting element must be operatively connected or to be formed with a plate through which passes a stud for engagement with the supporting element in the wall. The first 20 named type of bracket is generally referred to as the hickey type, while the second named is known as the center-knob type. It is the principal object of the present invention to 25 provide as a simple and inexpensive article of manufacture an appropriate adapter for engagement with a demountable fixture supporting plug and for operative engagement with the fixture to be supported. For the 30 purposes of this application the two most usual types of bracket are provided for by adapters designed to accommodate them, although it will be understood as the description proceeds that adapters of other 35 forms but intended for use under corresponding conditions and in similar ways may be provided by one skilled in the art without departing from the spirit of the invention. It is to be further understood that 40 while a preferred form of plug for supporting fixtures demountably has been illustrated and the improved adapters designed for association therewith, the inventive thought is of sufficient breadth to include 45 adapters which might be associated in much the same way with fixture supporting plugs of other character.

The preferred embodiments of the invention will be described with greater particularity in connection with the drawing, wherein—

Figure 1 is a view, partly in vertical section and partly in side elevation, of a wall bracket secured to an improved hickey

adapter which is engaged with a removable fixture supporting plug.

Figures 2 and 3 are detail views in plan and front elevation, respectively, of the hickey adapter shown in Figure 1.

Figure 4 is a view similar to Figure 1 but 60 showing another type of adapter associated with the plug of Figure 1 and carrying a center-knob type of plug.

Figures 5 and 6 are detail views in plan and front elevation, respectively, of the 65 adapter shown in Figure 4.

While the invention is not concerned with the details of construction of the type of fixture supporting plug with which the improved adapters are to be associated, it has 70 grown out of the trend of the art towards the demountable supporting of fixtures and appliances. While many different devices have been proposed for thus demountably supporting fixtures, the plug *a* of the type 75 covered by said copending application is the one with which the improved adapters have been actually placed in use. This plug *a* carries one or more curved supporting members *a'* which enter slots provided therefor 80 in a wall receptacle indicated by dotted lines at *b*. On the body of the plug *a* is carried an upstanding lug *a''* with which may be engaged the usual bridge or strap to be found on the back of many modern brackets. Since 85 it is true, however, that all brackets are not provided with such bridges or straps, some provision must be made for supporting all standard forms of fixtures, no matter how constructed, and it is obviously desirable, if 90 not necessary, to make it unnecessary that a different type of supporting plug be manufactured and sold to accommodate each type of bracket. Even if it were practical from the manufacturers' and dealers' standpoint 95 to put out such different types of plugs for different types of brackets, a severe limitation on the range of usefulness of such plugs would be imposed thereon since different types of brackets could not then be accommodated by any one plug, and great care would 100 always have to be used in selecting and keeping on hand plugs for different brackets. The present invention seeks to remove these and many other apparent objections to removable supporting devices for fixtures and insure them that broad and universal field 105 of application which they should fill by pro-

viding simple and inexpensive and interchangeable adapters which may be quickly and readily engaged with the supporting plug for which they may be designed and afford the required type of connection for the bracket to be supported. For any given type of supporting plug, such as the plug *a* illustrated herein, the connecting means for the adapters to be associated therewith may be of standardized form so that any one of many different adapters may be engaged with such a type of plug, no matter where found. In realizing this very important object of the present invention, the two types of adapters *c*, *d*, illustrated in Figures 1 and 4 both have the same form of retaining means for engagement with the plug *a*. For instance, the adapter *c* is provided in its upper face with a slot *c'* which may be passed over the upstanding lug *a'* of the plug *a*, while the other type of adapter *d* is also formed in its upper part with a similar slot *d'*. This degree of interchangeability of adapters for different types of fixtures is necessary for a successful realization of the requirements of the broad aspects of the present invention. The construction of the bodies of the adapters will depend upon the type of fixture to be accommodated. Provision is made in the illustrated embodiments for the accommodation of a bracket, such as *e*, having a threaded stem *e'* for its support, and for a second type of bracket *f* which is carried with a plate *f'* through which passes what is known as a center-knob *g*.

The adapter *c* for supporting the type of bracket exemplified at *e* will be called for convenience the hickey adapter, since it has been general practice to support this style of bracket by means of a threaded hickey. The adapter *c* may be stamped from a single blank and be given the form illustrated, wherein there is an upper horizontal section *c'*, part of which rests on the upper edge of the plug *a*, a substantially vertical section *c*² in which is drawn and tapped an opening *c*⁴ to receive the threaded end *e'* of the bracket *e*, and inclined webs *c*⁵ extending from points below near the tapped opening *c*⁴ to the lower face of the plug *a* and terminating in a flanged cross-piece *c*⁶ which bears against the face of the plug *a* and is positioned thereon somewhat by means of the flange *c*⁷ which turns under the lower front edge of the plug.

The hickey adapter *c* has been described with some degree of particularity, in its preferred form, since, as an article of manufacture, it embodies many advantageous details of construction which tend to cheapness, strength and simplicity.

The other type of adapted *d* illustrated herein for the purpose of indicating the scope of the invention may be not unlike

the adapter *c*, although it is intended for use with a center-knob type of fixture. It may be of even greater simplicity and less expensive than the adapter *c*. As illustrated, its upper portion *d*² is stamped out as a plain plate with the slot *d'* therein. Integral with its upper section *d*² but extending downwardly at right angles thereto is a vertical portion *d*³, wherein is tapped a hole *d*⁴ to receive the inner threaded end *g'* of the center-knob *g*. The adapter *d* may have a lower web portion *d*⁵ bent inwardly from the vertical section *d*³ and adapted to have its inner edge rest against the front face of the plug *a*.

This adapter *d*, considered as an article of manufacture, satisfies all of the requirements of cheapness and simplicity.

From the foregoing description the manner of using the improved adapters, or adapters constructed in accordance with the inventive thought but designed to accommodate other types of fixtures, should be apparent. In the first place, it is evident that the plug *a*, considered alone, will support a bridge type of bracket when the strap is engaged with the lug *a'*. If it is desired to support a bracket, such as *e*, having a threaded stem, on the same plug *a*, the adapter *c* may be readily engaged with the plug by dropping it down over the plug with the lug *a'* extending upwardly through the slot *c'*. The proportion of all associated parts may be such that after the adapter *c* has been threaded on to the stem *e'* and engaged with the lug *a'* the supporting members *a'* of the plug *a* may be passed into the receptacle *b* for support of the bracket. If it were thought desirable to engage the plug *a* with the bracket *e* with some degree of permanency, screws *h* which pass through the plug *a* might be of such length as to engage threaded holes *c*⁸ in the transverse bearing strip *c*⁹ of the adapter. When the screws *h* are thus engaged with the adapter *c*, it will be retained with some degree of permanency on the plug, although for quick interchangeability such screws will not ordinarily be so engaged. While no mention has been made herein of the slip canopy *i*, it will be understood that such canopy might be slidably mounted on the stem of the bracket *e* and fastened in place by a set screw *i'*, as is the usual practice.

The manner of using the adapter *d* will also be clear. Ordinarily it will be engaged with the lug *a'* and the plug *a* forced home. The plate *f'* will then be properly positioned and the center-knob *g* passed through the plate and its threaded stem *g'* engaged with the tapped opening *d*⁴ in the front web *d*³ of the adapter.

I claim as my invention:

1. An adapter for a demountable electrical connecting and supporting plug for

- fixtures, the plug having an upstanding lug for engagement with a fixture having a bridge, an inwardly projecting member on said adapter, a slot in said member for detachable engagement with said lug, threaded means on the adapter for supporting the fixture, and means co-operating with the slot for supporting the adapter from the plug.
2. A device for attaching an electric wall bracket to a fixture supporting plug having a hook, the said device having a threaded portion for engagement with the bracket, an extension above the threaded portion having a slot for engaging the hook of said fixture plug, and an extension below the threaded portion having a bearing surface

to prevent sagging of the device below normal position when attached to the hook of said fixture plug.

3. A one-piece device for connecting an electric wall bracket to a wall fixture supporting plug having a hook, comprising means for attaching the device to a wall bracket, a slotted portion for engaging the hook of the fixture plug, a bearing surface for engagement with the face of the fixture plug, and means for spacing the said engaging means away from the said face of the fixture plug.

This specification signed this 25th day of March, A. D. 1921.

ERNEST CANTELO WHITE.
